UNITED STATES PATENT OFFICE.

MYRON J. BRUMMITT, OF TOLEDO, OHIO.

PAPER AND MAGAZINE HOLDER.

Application filed October 17, 1924. Serial No. 744,245.

To all whom it may concern:

Be it known that I, MYRON J. BRUMMITT, a citizen of the United States, residing at Toledo, in the county of Lucas and State 5 of Ohio, have invented new and useful Improvements in Paper and Magazine Holders, of which the following is a specification.

This invention relates to clamping devices and has for its object the provision of a 10 novel device adapted to be mounted upon a house, wall or other support for the purpose of holding papers, magazines and similar articles delivered by mail carriers and others.

An important and most specific object is 15 the provision of a device of this character which is of a resilient nature whereby to clampingly engage against the newspaper, magazine or the like and hold the same firmly so that it cannot drop down and be- 20 come lost or blown away.

Another object is the provision of a device of this character which, in actual practice, may be formed from a single length of 25 spring wire bent and coiled into the necessary shape and which will consequently be extremely simple and inexpensive in manu- 30 facture.

With the above and other objects and ad- 35 vantages in view, the invention consists in the details of construction to be hereinafter more fully described and claimed, and illus- 40 trated in the accompanying drawings in which:

Figure 1 is an elevation of the device look- 45 ing at the front thereof, and

Figure 2 is a vertical section taken on the line 2—2 of Figure 1.

Referring more particularly to the drawings, I have shown my holder or clamp as 50 formed from a single length of resilient wire of suitable gauge and finished in any de- 55 sirable manner not only to have a pleasing appearance but also to be capable of with- 60 standing the weather. In constructing the 65 device, the length of wire, indicated broadly by the numeral 10, is bent at its center to define a U-shape yoke 11, at the ends of the arms 12 of which the wire is formed into several coils 13 from which it is extended laterally at 14 and brought along straight 70 stretches 15 spaced from and parallel with the arms 12 of the yoke. At the ends of the lengths or stretches 15 the wire is coiled several times as shown at 16 and extended 75 from the ends thereof in spaced parallel re-

lationship to the stretches 15 to define attaching arms 17 terminating in eyes or loops 18 through which may be passed suitable se- 80 curing members such as screws 19 or the like whereby the device may be properly anchored upon the wall A of a building or upon any other support. To describe the base generally, the device might be said to include three U-shaped portions spaced apart but connected by coils. Attention is 85 directed to the fact that the arms 12 of the yoke and the arm members 15 are corre- 90 spondingly or similarly curved so that the coils 13 will be spaced away from the wall or other support. This curvature of these 95 members also brings the bight portion of the yoke 10 away from the wall so that it may be conveniently grasped by a letter-car- 100 rier or other persons and swung upwardly to permit of the insertion of a newspaper, 105 magazine or the like between the yoke 10 and the members 15 and 17. If desired, the articles to be held may simply be inserted 110 downwardly between the coils 13 and wall of the building or other support. Naturally 115 there is no limitation as to the exact manner of use especially as it is apparent that either arrangement may be used as preferred.

From the foregoing description and a 120 study of the drawings, it will be apparent 125 that I have thus provided a very simply constructed, inexpensive and easily installed and operated device for the purpose speci- 130 fied which will be a great saver of time and 135 labor, and which will be of additional ad- 140 vantage inasmuch as it will prevent papers and the like from being blown away and lost 145 or destroyed. Furthermore, owing to the 150 fact that the device is constructed from a 155 single piece of material it is apparent that 160 there are no separate moving parts to get 165 out of order so that the device should pos- 170 sess great durability.

While I have shown and described the pre- 175 ferred embodiment of the invention, it 180 should be understood that I reserve the right 185 to make such changes in the form, construc- 190 tion, and arrangement of parts as will not 195 depart from the spirit of the invention or 200 the scope of the subjoined claim.

Having thus described the invention, I 205 claim:

A clamping device of the character de- 210 scribed formed from a single length of wire bent to define a U-shaped central yoke mem-

ber curved longitudinally throughout its length, the wire being coiled at the ends of the arms of said yoke and extended laterally, the wire being further extended from said

5 lateral portions in spaced substantially parallel relation to the arms of the yoke and longitudinally curved, the wire being ad-

ditionally coiled at the ends of said last named portions and extended in spaced relation therewith to define straight stretches 10 terminating in eyes.

In testimony whereof I affix my signature.

MYRON J. BRUMMITT.
